UNITED STATES PATENT OFFICE.

HARRISON D. FLEGEL, OF RACINE, WISCONSIN.

PEN ATTACHMENT FOR PENCILS.

1,345,155.

Specification of Letters Patent. Patented June 29, 1920.

Application filed May 20, 1919. Serial No. 298,469.

To all whom it may concern:

Be it known that I, HARRISON D. FLEGEL, a citizen of the United States, and resident of Racine, in the county of Racine and State 5 of Wisconsin, have invented certain new and useful Improvements in Pen Attachments for Pencils; and I do hereby declare that the following is a full, clear, and exact description thereof.

10 This invention pertains broadly to improvements in pens, and more particularly to pen attachments for ordinary or standard types of pencils.

One of the objects of the present invention 15 is to utilize the qualities of certain standard types of pencils to aid in forming writing fluid for use with pens attached to the pencils. In this connection I provide a pen attachment which can be readily slipped over 20 the pointed end of one of such pencils so that when the combined device is dipped in water, a quantity thereof will be trapped and a portion of the lead of the pencil will be dissolved to form writing fluid.

25 Another object of the invention is to provide a very simply constructed and inexpensive attachment which can be readily formed from sheet material, and one which can be easily associated with the pointed end of the 30 desired type of pencil.

With these and other objects and advantages in view, the invention resides in the novel features of construction, combination and arrangement of parts which will be 35 hereinafter more particularly described and claimed and shown in the drawing in which:

Figure 1 represents a portion of the pointed end of a pencil having my improved attachment mounted thereon, the same being 40 shown in section.

Fig. 2 is an elevational view of the parts shown in Fig. 1, the usual closure cap having been removed.

Fig. 3 is a detail transverse sectional view 45 on the plane of the line 3—3 of Fig. 1.

Fig. 4 is a detail elevational view of a modified form of the attachment, and

Fig. 5 is a transverse sectional view on the line 5—5 of Fig. 4.

50 In Figs. 1, 2 and 3 of the drawing I have illustrated a standard commercial pencil 1 which includes a lead strip 3 inclosed in a usual protective casing, the latter being pointed as at 2 to expose the lead strip 3.

55 This lead is preferably of the so-called indelible or copying type. The lead is exposed

in the same way as if the pencil was to be used in an ordinary manner, as for instance by a pencil sharpener.

The attachment which is to be used with 60 this pencil and which forms a holder for a pen 4 consists of a sleeve 5, one portion of which is cylindrical as at 6 and is adapted to engage the unsharpened portion of the pencil adjacent the pointed end 2. An annular 65 shoulder 7 is formed on the sleeve substantially midway its ends against which the open end of a cap 8 abuts. The latter part is designed to house the pen 4 and adjacent associated parts as in the case of the usual 70 fountain pen.

The part of the sleeve 5 disposed outwardly of the shoulder 7 has its free end restricted and bent out of "round" as at 9 thereby forming a seat for the shank of the 75 pen 4. This inclines the point of the pen inwardly toward the longitudinal axis of the pencil whereby the lead 3 of the latter is positioned relatively close to the intermediate portion of the pen and thus provides a 80 positive feed.

Associated with the pen 4 to form a liquid reservoir is a feeder tongue 10, the inner end of which is increased in width and bent substantially semi-cylindrically as at 11. The 85 part 11 is slipped into the outer end of the sleeve 5 on the opposite side thereof from the seat 9 and is frictionally held therein by being of slightly different curvature from the latter. From Figs. 1 and 3 it will be appreciated that the longitudinal edges of the part 11 of the tongue 10 are designed to be engaged by the similar edges of the shank of the pen 4 to thereby hold said pen in its seat and against rotation. The tongue 10 90 is extended outwardly of the end of the pencil lead and is curved toward the point 4 and engaged therewith.

The operation of the parts described is probably readily obvious from the drawing, 100 but may be briefly set forth substantially as follows: After the attaching portion 11 of the feeder tongue 10 has been disposed in the outer end of the sleeve 5, the pen 4 may be slid into its seat, said pen and the tongue being so arranged that the point of the former is engaged with the end of the latter as in Fig. 1. The attachment including the sleeve 5, the pen 4 and the tongue 10 may then be slid over the pointed end of the pencil 1 110 until the lead thereof is located outwardly of the end of the sleeve and between the pen 4

and tongue 10. Now when the device is dipped into water or other liquid, a quantity of the same will be caught between the pen 4 and tongue 10 and only fed from the former by capillary action as is customary in devices of this character. The lead of the pencil being in the trapped water will be slowly dissolved to color said water and form writing fluid thereof. As the lead becomes dissolved the pencil may be resharpened and the sleeve slid farther onto the plain portion of the pencil.

In Figs. 4 and 5 a modification of the invention is shown in which the sleeve 5' and the feeder tongue 10' are formed from a single piece of sheet material. The sleeve consists of a blank of sheet material rolled longitudinally into substantially cylindrical shape, the tongue 10' being extended beyond the outer end thereof for coöperation with a pen 4', the shank of which is disposed in a seat 9' inclined in substantially the same manner as the seat 9 of the above mentioned form of the invention. Ribs or the like 11' are formed on the inner wall of the outer end portion of the sleeve 5' to be engaged by the longitudinal edges of the shank of the pen 4', said ribs forming stops for the same purpose as the longitudinal edges of the part 11.

In addition to the changes in the forms of the invention shown in the two sets of figures, various other modifications may be made in the form and proportion and in the manner of application without departing from or sacrificing any of the advantages of the invention or the results to be obtained therefrom. The obvious advantages of the invention are the cheapness of construction, ease of and inexpensive operation, ready application and adjustment of parts, and ease of replenishment of the portions which are used up.

I claim:

45 1. An attachment for a commercial pencil comprising a member, one end of which receives the sharpened end of a pencil, and a pen carried by the other end of the member, said member receiving liquid and holding 50 the same in contact with the sharpened end

of the pencil to provide writing fluid for the pen.

2. An attachment for a commercial pencil having a portion only of its lead exposed, comprising a member adapted to retain a liquid in contact with the pencil lead when applied thereto, and a writing point carried by said member, the body of the pencil serving as a handle for said writing point.

3. An attachment for a commercial pencil comprising a tubular member, a pen carried by one end of the member, and a tongue carried by the member and coacting with the pen to support liquid to feed from said pen, the other end of the member remote from the pen being adapted to receive a sharpened commercial pencil in position to dispose the lead thereof in contact with liquid supported between the tongue and pen to thereby provide writing fluid.

4. The combination with a pencil, of a holder sleeve disposed around said pencil inwardly of the pencil point, a tongue projecting from one end of the sleeve and extended outwardly of the pencil point on one side thereof, a pen secured to the sleeve and disposed on the opposite side of the pencil point from the tongue and extended outwardly of said point to define a reservoir receiving said point, said tongue being engaged with the pen outwardly of the pencil point whereby upon moisture being disposed therein, writing fluid will be supplied to the pen.

5. The combination with a pencil, of a holder sleeve disposed around said pencil, the portion of the sleeve adjacent the pencil point being contracted to form a pen seat, and a pen disposed in said seat, the point of the pen being inclined inwardly toward the longitudinal axis of the pencil to position the pen in close proximity to the pencil point, writing fluid being supplied to the pen from the pencil point upon moisture being applied to the latter.

In testimony that I claim the foregoing I have hereunto set my hand at Racine, in the county of Racine and State of Wisconsin.

HARRISON D. FLEGEL.
